CLAIM

The ornamental design for a combined surgical occluding and cutting instrument, substantially as shown and described.

DESCRIPTION

FIG. 1 is a side perspective view of a combined surgical occluding and cutting instrument showing our new design;

FIG. 2 is a side elevational view of the device of FIG. 1;

FIG. 3 is a right side elevational view thereof;

FIG. 4 is a left side elevational view thereof;

FIG. 5 is a top plan view as seen from FIG. 1; and

FIG. 6 is a bottom plan view as seen from FIG. 1.

Fig. 3.

Fig. 4.

Fig. 5.

Fig. 6.
